FIG. 6 INVENTOR.
Wallace Wenzel

BY
Frank A. Cutler,
ATTORNEY.

UNITED STATES PATENT OFFICE.

WALLACE WENZEL, OF SOUTH HADLEY FALLS, MASSACHUSETTS.

TRUSS.

1,188,709.

Specification of Letters Patent. Patented June 27, 1916.

Application filed January 18, 1916. Serial No. 72,841.

To all whom it may concern:

Be it known that I, WALLACE WENZEL, a citizen of the United States of America, residing at South Hadley Falls, in the 5 county of Hampshire and State of Massachusetts, have invented a new and useful Truss, of which the following is a specification.

My invention relates to improvements in 10 hernial trusses, and resides in a hollow perforated presser member or pad, which is provided with an exterior guard or shield arranged to hold the clothing away from said pad, and certain peculiar attaching 15 means for the straps with which said pad is secured in position on the body, together with such auxiliary and subsidiary parts and members as may be needed to render the truss complete, all as hereinafter set 20 forth.

An object of my invention is to produce a comparatively simple and inexpensive truss which can be maintained over the hernial spot with a steady pressure and 25 without liability of displacement from any action or movement of the body and legs of the wearer.

A further object is to provide a ventilated, hence cool and comfortable, truss pad; 30 provision being made for the circulation of air freely in and through such pad. Although there can be no circulation of air through the pad at the place where the same contacts with the flesh, when said pad 35 is in position, the circulation at other points keeps the pad and the flesh both cool, and perspiration is prevented by the presence of a perforated surface next to the flesh. Herein is an important and valuable fea- 40 ture of my invention.

In order to effect the thorough and constant ventilation of the pad I provide the same with the shield to which reference 45 has been made. This shield holds the clothing away from the front or outer side of the pad so that the perforations in such side are not covered and closed by such clothing.

Still another object is to provide convenient, secure, and efficient means wherewith 50 or whereby the pad and straps can be readily connected and disconnected.

Other objects and advantages will appear in the course of the following description.

55 I attain the objects and secure the advantages of my invention by the means illus-

trated in the accompanying drawings, in which—

Figure 1 is a perspective view of a single truss which embodies a practical form of 60 my invention; Fig. 2, a perspective view of a double truss which, aside from the double feature, is similar to the truss shown in the preceding view, the left-hand shield being omitted; Fig. 3, an enlarged detail of one 65 of the strap connections; Fig. 4, an enlarged front elevation of the pad and connections shown in Figs. 1 and 2, without the shield; Fig. 5, a central vertical section through the pad shown in the preceding 70 view, taken on lines 5—5, looking in the direction of the associated arrow, in the said view, the shield being in place and the connections omitted; Fig. 6, a front elevation of a modified form of pad and connections, 75 without the shield, and, Fig. 7, a central vertical section, on lines 7—7, looking in the direction of associated arrow, Fig. 6, the shield being here included.

Similar numerals refer to similar parts 80 throughout the several views.

The truss comprises, with a pad 1 and its accessories which will presently be described, the necessary straps which include a body belt 2 and a crotch band 3. The 85 belt 2 and band 3 may be made of any suitable material and in any suitable manner, but I prefer to employ a double or looped strap for each, securing the free ends of the belt strap with an ordinary tri-bar 90 clasp 4, and using a similar clasp with which to secure the free ends of the crotch strap. The clasps 4 are especially adapted for my purpose because they are flat, and even though tongueless afford the necessary 95 security, owing to the frictional resistance that exists when said clasps are in place on the straps. Being without tongues the clasps 4 can very readily be adjusted on the straps or the latter through said clasps. 100

Preferably an adjustable connection is formed by the crotch band 3 with the belt 2, so that the rear looped terminal of said band can be located at the most suitable place on said belt and attached or secured thereto at 105 such place, and to this end one terminal of the band strap is carried over said belt, after being passed up through the band clasp 4, and then brought down through said clasp again, while the other strap terminal is 110 passed through said clasp over the bottom bar thereof, as clearly shown in Fig. 3.

After the band 3 has been adjusted on the belt 2, the band clasp 4 is forced upwardly so as to cause the band strap tightly to embrace said belt. For the double truss an additional crotch band 3 and a second pad 1 are provided, also a looped-strap connection 5, with a clasp 4 therefor and thereon, to connect the two pads.

At each looped terminal of the belt 2 and the front looped terminal of the crotch band in each case, also at each looped terminal of the connection 5, is a fastener 6. The fasteners 6 for one type of pad herein shown have slots 7 therein, while the fasteners 6 for the other type of pad herein shown are provided with hooks 8. The inner ends of the slots 7 are enlarged as represented at 9.

Each pad 1 is hollow and has perforations 10 in both the back and front sides. Said 20 pad may be made of metal, such as aluminum, and constructed in two parts or sections which are screw-threaded at their edges and united by being screwed together, as represented at 11 in Figs. 5 and 7.

25 A shield 12 is provided for each pad 1, such shield having a central stem 13 which is tapped into an axial socket 14 that projects inwardly from the back side of said pad. The stem 13 supports the shield 12 in front of the outside face of the pad to which it is attached, and at a sufficient distance from such face to prevent the clothing from closing the perforations 10 in the front side of said pad, and to provide room for the 30 ends of the fasteners 6 that engage the pad, when such ends are in place. The space between the pad and its shield may not be sufficient to enable the fasteners to be attached to and detached from such pad, and when 35 such is the case it is necessary to remove such shield, by unscrewing the stem 13 thereof, before said fasteners are attached or detached, immediately afterward replacing said shield, unless, when the parts are detached, it be desired to delay replacing the shield until the parts are again attached.

The pad 1, in Figs. 1, 2, 4 and 5, is equipped with three radially-movable posts 15 which have heads 16. Each post 15 extends through and operates in a radial slot 17 in the front of the pad 1, with its head 16 and a portion of said post outside of said front, and said post has affixed to the inner end thereof a guide plunger 18, the post and 20 plunger being at right angles to each other, and the junction between such members being near the inner end of said plunger. Each plunger 18 operates in a radial socket 19 in the pad, such socket having in the front side thereof a slot 20 which is parallel with and directly behind one of the slots 17, and through and in which the post 15 attached to such plunger extends and operates. A spiral spring 21 is located in each socket 19, 25 between the closed outer end thereof and the

post 15 that extends into such socket, partially encircling the plunger 18 attached to said post, and normally retains said post at the inner ends of the slots 20 and 17 in which the post is located. The slots 17 and 20, 70 which thus limit the inward movement of the posts 15, also serve as guides for said posts. As stated above, normally the posts 15 are at the inner ends of their travel, as represented in Figs. 2, 4 and 5. An axial 75 opening 22 is provided in the front of the pad 1 now being considered to accommodate the shield stem 13. The posts 15 are designed to afford points of attachment for the slotted fasteners 6, such fasteners being 80 slipped on and off over the heads 16, which latter are receivable in the enlargements 9 of the slots 7, in the manner customary with fasteners of this type.

The pad, illustrated in the last two views, 85 has merely a central front opening 23, into which the fastener hooks 8 are introduced, and the edge of which serves as the anchorage for such hooks. The shield 12 for this pad is supported by its stem 13, which 90 latter passes through the opening 23, in front of said opening and prevents the clothing from covering either this opening or the adjacent perforations 10. The shield in this as in the other case itself stands clear of the 95 pad and affords clearance for the fasteners.

The slotted fasteners 6 form pivotal connections with the posts 15 of such a nature that the body straps can move freely, relative to the attached pad or pads, without 100 disturbing the latter or turning or twisting the same on the hernial spot; and likewise the hooks 8, on the other fasteners, fulcrum on the edge of the opening 23 in such a manner as to permit entire freedom of strap 105 movement, so that the attached pad or pads are not disturbed thereby.

The springs 21, in the first type of pad, afford the required amount of flexibility for the body straps, yielding by compression 110 when such straps are drawn away from the pad, and expanding to take up slack, thus keeping said straps taut at all times, so that the straps need not be made of elastic material, as is necessary in the case of the straps 115 used with the second type of pad, although elastic material may be employed, if desired, for the first-mentioned straps.

The single truss is applied, after the shield 12 has been removed, by encircling the body 120 with the belt 2 and attaching the belt fasteners 6 to the pad 1, locating said pad directly over the hernial spot, and carrying the band 3 between the legs and up and attaching the band fastener 6 to said pad. 125 Then the shield 12 is secured to the pad by screwing the shank 13 of said shield into the socket 14 in said pad. The slotted fasteners 6 are slipped into place, over the heads 16 and then moved outwardly to locate the 130

posts 15 in the outer ends of the slots 7, such outer ends being between the front of the pad and the heads 16. The fasteners 6 which are provided with the hooks 8 are simply hooked into the open front of the pad. The first time that the truss is applied, and at other times if necessary, the belt 2 and the band 3 are adjusted, as may be required to locate the pad in proper position and fit securely but comfortably the body of the wearer, by drawing the straps through the clasps 4 to lengthen or shorten the parts as needed, and any required adjustment of said band on said belt may be made in the manner hereinbefore described.

The manner of applying and fitting the double truss to the body is very similar to that explained above of applying and fitting the single truss, only with the double truss there are two crotch bands to attach and adjust, instead of one, the connection 5 to be attached to the two pads and adjusted, and two shields 12 to be placed in position, instead of one.

The single truss is removed from the body by detaching or disconnecting the crotch band 3 and one looped end of the belt 2 from the pad 1. The double truss is removed from the body by disconnecting both crotch bands from the pads and one looped end of the belt or of the connection 5 from the adjacent pad. In the present constructions it is necessary to remove the shield or shields from the pad or pads before proceeding to unfasten the truss for removal, as previously observed.

As is plainly to be seen, these pads are thoroughly ventilated and therefore sanitary and comfortable.

When once properly adjusted, the pad does not rub on the flesh, and its shield prevents the clothing from rubbing directly on the pad, unless it be on the outer edge thereof where the same can do no harm.

The shape, size, arrangement, and construction of the truss elements may be modified or changed, even more than I have herein specifically shown and explained, without departing from the spirit of my invention or exceeding the scope of my claims.

What I claim as my invention, and desire to secure by Letters Patent, is—

1. The combination, with a hollow perforated truss pad, of a circular shield provided with a central stem which extends rearwardly into said pad and is attachable

thereto, said stem being adapted to support said shield in front of said pad.

2. The combination, in a truss, with a belt and a crotch band provided with fasteners, of a pad provided with longitudinally movable non-oscillating spring-pressed members having parts adapted to be engaged by said fasteners, said members being radial to said pad.

3. The combination, with a hollow truss pad provided with interior radial sockets, said pad and sockets having radial slots in their front sides, of longitudinally-movable guides in said sockets, posts attached to said guides and extending outwardly at right angles thereto through said slots, and springs arranged in said sockets to force said guides toward the axial center of said pad and said posts toward the inner ends of said slots.

4. The combination, in a truss, of a belt, a crotch band, a pad provided with longitudinally movable non-oscillating spring-pressed members, having attaching parts, said members being radial to said pad, and fasteners connected to said belt and band, and adapted to be pivotally engaged with said attaching parts, and to swing in the same general plane wherein the pad is located.

5. The combination, in a truss, with a radially slotted pad, fastener-engaging members arranged to reciprocate in the slot in said pad, and springs arranged to force said members toward the inner ends of said slots, of a shield provided with a central stem which extends into said pad and is attachable thereto, said stem supporting said shield in front of said pad and over said fastener-engaging members.

6. The combination, in a truss, of a belt and a crotch band provided with fasteners, of a radially slotted pad, fastener-engaging members arranged to reciprocate in the slots in said members toward the inner ends of said slots, and a shield provided with a central stem which extends rearwardly into said pad and is attachable thereto, said stem supporting said shield in front of said pad and of said fastener-engaging members and fasteners attached thereto.

WALLACE WENZEL.
